Attorneys.

UNITED STATES PATENT OFFICE

ALBERT HOSSFELD, OF WINONA, MINNESOTA

ANGLE-BAR BENDING DIE

Application filed March 30, 1931. Serial No. 526,251.

This invention relates to a bending machine, and while the invention might have various applications, it particularly was designed as a bending machine of the die type, for bending angle bars. It has been quite difficult to bend angle bars in a machine of this type, as an angle bar tends to become very much distorted in a bending operation. Applicant has previously perfected a machine for bending angle bars on the curve with the flange of the angle bar perpendicular to the axis of the curve or bend being concave. The present machine is designed to bend an angle bar with the flange which is substantially perpendicular to the axis of bend being on the convex side of the curve. It is believed that this has not heretofore been accomplished on a die type of machine.

It is an object of this invention, therefore, to provide a simple and efficient device for bending an angle bar with one flange of the bar which is substantially perpendicular to the axis of the bend or curve being on a convex curve.

It is a further object of the invention to provide a device for bending an angle bar as set forth in the preceding paragraph comprising relatively movable dies for engaging one flange of the bar, which flange is parallel to the axis of the bend, and having means with flat surfaces for engaging the other flange of the bar so that the bar is bent without being distorted.

It is still another object of the invention to provide a device for bending an angle bar with one flange perpendicular to the axis of bend, and bent on a convex curve comprising relatively movable dies for engaging and gripping said flange and having other surfaces which engage the flange which is parallel to the axis of bend, means being provided for relatively moving the parts engaging the first mentioned flange as the bar is engaged and bent.

It is still another object of the invention to provide a device for bending an angle bar with one flange substantially perpendicular to the axis of bend, and bent on a convex curve, comprising a pair of dies, a flat surface adjacent said dies engaged by one side of

the other flange of the bar, one of the dies having a movable portion engaging the other side of said latter flange with a flat surface, wedge or cam means being provided for moving said portion of said die as the dies are brought to position engaging said bar.

It is more specifically an object of the invention to provide a hand operated machine for bending an angle bar with one flange perpendicular to the axis of bend, and bent on a convex curve, comprising relatively movable dies having mating convex and concave surfaces, one of said dies being pivoted for swinging movement toward the other and the other die being stationary, a lever swingable about a fixed axis and having means engaging the movable die to swing the same toward the stationary die.

These and other objects and advantages of the invention will be fully set forth in the following description made in connection with the accompanying drawing, in which like reference characters refer to similar parts throughout the several views and in which:

Fig. 1 is a plan view of the device, some parts being broken away;

Fig. 2 is a horizontal section taken on line 2-2 of Fig. 3;

Fig. 3 is a view in side elevation;

Fig. 4 is a vertical section taken on line 4-4 of Fig. 2, and

Fig. 5 is a vertical section taken on line 5-5 of Fig. 2.

Referring to the drawing, a device is shown which comprises brackets 10 and 11 which may be secured to any suitable support such as a bench or table top 12. Brackets 10 are shown as secured to member 12 by the headed and nutted bolts 13. Brackets 10 have secured thereto by the headed and nutted bolts 14 a frame 15 comprising spaced bars 15a and 15b having portions adjacent bracket 10 which are parallel and quite close together, and which are spaced by the spacing bushings 16. One of these bushings surrounds one bolt 14 and the other surrounds a headed and nutted bolt 14a passing through bars 15a and 15b. Bars 15a and 15b diverge between brackets 10 and 11 and have outer

parallel portions spaced quite a greater distance apart, the same being spaced by a spacing member or bushing 17. The bars 15a and 15b are apertured to receive a headed and nutted bolt 18 forming a pivot for a swinging member 19 having a hub portion disposed between the bars 15a and 15b. Member 19 is formed adjacent one end with an inclined surface 19a. Member 19 is of angular shape in transverse section as shown in Figs. 4 and 5 and has a horizontally projecting portion provided with a flat top surface 19b. This horizontal portion and flat surface extend over quite a large extent as shown in Figs. 1 and 2, having a curved portion at one end as shown at the bottom of Fig. 1, and said portion also has formed therein a semi-cylindrical slot 19d. Member 19 has its vertically extending portion provided with spaced projecting ribs 19c and as shown in Figs. 4 and 5, these have their front or bottom surfaces 19e inclining downwardly at an angle of substantially 45° toward said vertical portion. Member 19 constitutes a die member and the same has another member or portion 20 having a front surface with a curved portion 20a and a straight portion 20b which extends substantially tangentially to said curved portion. Member 20 is provided with spaced slots receiving portions 19c and said slots are provided with surfaces 20c inclined at the same angle as the surface of ribs 19c. Member 20 is substantially of rectangular shape in vertical cross section, except at the slots which receive ribs 19c where the section is as shown in Fig. 4. Another die member 21 is provided, having a surface, a portion of which 21a is curved and opposed to the surface 20a and another portion 21b of which is flat and tangential to portion 21a and opposed to the flat portion 20b of die member 20. Die member 21 extends between the bars 15a and 15b and is pivoted therebetween and between a pair of bars 22 and 23, which bars are disposed respectively at the inner sides of bars 15a and 15b at their outer ends. The lower surface of member 21 is flat and extends over and substantially in contact with the surface 19b. A pivot member comprising the headed and nutted bolt 24 extends through bars 15a and 15b, bars 22 and 23, and the die member 21. Said bolt also extends through a washer or collar 25 disposed beneath member 21 and between the same and bar 23. Bars 22 and 23 have another headed and nutted bolt 26 extending therethrough and therebetween on which is journaled between said bars a roller 27. Bars 22 and 23 are secured at their other ends to a lever member 28 which has a handle portion 29 extending therefrom. Members 28 and 29 can be made as long as desired, and in practice, these are of considerable length, so that a strong leverage can be obtained.

In operation, when the angle bar 30 is to

be bent, lever 28 is swung as shown in Fig. 1 and members 19 and 20 are moved away from member 21. The bar 30 is then placed on the member 19 with the bottom surface of one flange engaging surface 19b as shown in Figs. 1, 4 and 5. Lever 29 is now swung in a clockwise direction as seen in Fig. 1, and roller 27 engaging the surface 19a swings members 19 and 20 toward the member 21 so that the vertically extending flange of the bar is as shown in Fig. 1 engaged between the members 20 and 21, said flange engaging the end portions of member 20 at one side and being engaged at its other side by the surface 21b. The operator now continues to swing lever 29 and roller 27 moves member 19 further, so that pressure is exerted on member 20. This pressure causes the surfaces 20c to engage the surfaces 19e and member 20 is cammed or wedged downwardly so that its lower flat surface engages the top of flange 30a of angle bar 30, said flange now being gripped between the bottoms of member 30 and the surface 19b. Continued movement of lever 29 brings the curved surfaces of members 20 and 21 closer together, and the flange 30a is stretched as it is bent and the angle bar tends to collapse to a smaller angle than a right angle. The vertical flange 30b warps over and continued movement of members 20 and 21 brings this flange snugly between the surfaces 20a and 21a as well as 20b and 21b, and the flange is again straightened up so that the angle bar has been bent and is still a perfect right angle. When the vertical flange 30b is tightly gripped between the members 20 and 21, the bending operation is finished. The operator then swings back lever 29 and the angle bar is moved a short distance further inward between the dies. The bending operation is then repeated. The bar is, of course, bent on the curve defined by the curved surface 20a and 21a. The member 19 and surface 19b extend some distance beyond the curved portion of the dies as the angle bar has a tendency to bend downward and must be supported in a horizontal position. The bar is thus kept in the plane of surface 19b. As the lever 29 is swung, the roller 27 moves along the surface 19a and the leverage on the member 19, of course, changes. The leverage can be varied by varying the degree of incline on surface 19a.

From the above description it will be seen that applicant has provided a simple and efficient device for bending an angle bar with one flange substantially perpendicular to the axis of bend, and bent on a convex curve. In making such a bend, it will be seen that the side flange must be stretched at its convex edge. In the actual operation, the flange is also compressed or stoved somewhat at the portion adjacent the other flange. It has been found in practice that there is

a neutral line substantially one-third of the distance from the vertical flange to the edge of the first mentioned flange. As above stated, when the bar is bent, the vertical flange tends to swing toward the other flange so that the angle between the flanges is reduced. This is corrected as the dies come together, and the proper right-angled shape of the flange is preserved. The bar is also restrained from bending lengthwise during the bending operation. The device bends the bar with great accuracy and the form of the bar is practically perfect after being bent. The bend can, of course, be made as extensive as desired, by successively moving the bar after each operation of the dies. The device has been amply demonstrated in actual practice and found to be very successful and efficient.

20 It will, of course, be understood that various changes may be made in the form, details, arrangement and proportions of the parts, without departing from the scope of applicant's invention, which generally stated, 25 consists in a device capable of carrying out the objects above set forth, in the parts and combinations of parts disclosed and defined in the appended claims.

What is claimed is:—

20 1. A device for bending angle irons having in combination, relatively movable die members having respectively convex and concave surfaces adapted to approach and recede, and having flat surfaces disposed respectively substantially at right angles to said convex and concave surfaces, and means for effecting relative movement of said dies to cause said convex and concave surfaces to approach, and means actuated by said movement for causing said flat surfaces to approach.

25 2. A device for bending angle irons having in combination, a member having a curved concave surface, a member having a curved convex surface, means having a flat surface extending at one side beyond said curved surfaces adapted to support one flange of an angle bar, the other flange of which is engaged between said curved surfaces, and a 30 means having a flat surface disposed parallel to said flat surface movable against said first mentioned flange by approaching movement of said concave and convex surfaces.

35 3. A die for bending angle irons having in combination, a die member having a convex surface, means having a flat surface extending at right angles to said surface, a second member having a flat surface disposed 40 parallel to said flat surface, and a third member having a concave surface parallel to said convex surface, and a common means for moving said third member towards said first member to bring said concave and convex 45 surfaces against the work, and to cause rela-

tive movement between said flat surfaces to bring them together.

4. A die for bending angle irons having in combination, a member having spaced portions projecting therefrom having inclined outer surfaces, a die member having slots receiving said portions having inclined surfaces engaging said inclined surfaces, said die member having a concave front surface and a flat lower surface, means having a flat 70 surface spaced from said flat surface, means for pressing work against said concave surface to cause said die to move its flat surface towards said second mentioned flat surface.

5. A die for bending angle irons having in combination, a die having a concave surface, means having a flat surface adjacent and substantially at right angles to said concave surface, said die having a movable portion having a surface substantially parallel to said flat surface, said die and movable portion having cooperating cam surfaces, whereby when pressure is exerted against said concave surface, said portion is moved to cause said flat surface and third 90 mentioned surfaces to approach, and a die movable towards said concave surface to press a flange of an angle bar against the same.

6. A die for bending angle irons having in combination, a die having a curved surface, means having a flat surface adjacent one side of said die, said die having a movable portion having a flat surface substantially parallel to said first mentioned flat surface, 100 wedge means causing movement of said portion for moving said flat surfaces toward each other, and a die having a surface movable toward said concave surface.

7. A die for bending angle irons having in combination, dies having convex and concave surfaces respectively for engaging opposite sides of the flange of an angle bar therebetween, means having a flat surface supporting one side of the other flange of said 110 bar, one of said dies having means with a flat surface for engaging the opposite side of said other flange, and wedge means causing said last mentioned means to move and its flat surface to engage said angle bar.

8. A die for bending angle irons having in combination, a die having a convex surface, a die having a concave surface adapted to press a flange of an angle bar against said convex surface, one of said dies being pivoted adjacent one end for movement toward the other die to cause said surface to approach, said pivoted die having an inclined surface thereon, a lever movable about a fixed pivot, and a roller carried by said lever engaging said inclined surface to move said pivoted die toward the other die.

9. A die for bending angle irons having in combination, a die having a concave surface with rectilinear elements and having 130

a flat surface extending substantially at right angles to said rectilinear elements of said concave surface, said flat surface extending quite a distance beyond said concave surface and arranged to support one flange of the angle bar, said die having means with a flat surface movable toward said first mentioned flat surface to engage said flange of said angle bar, another die having a convex surface adapted to oppose said concave surface, and means for moving said dies together for bending an angle bar.

10. A device for bending angle irons so that one flange is bent about an axis substantially perpendicular to the plane thereof, with its edge on a convex curve, comprising means having a convex surface, means for gripping one flange of an angle bar between flat surfaces, and means having a concave surface movable toward said convex surface for bending said first mentioned flange about the curve of said convex surface, and compressing the other flange between said concave and convex surfaces.
